(57) **CLAIM**

The ornamental design for a night stand, as shown and described.

DESCRIPTION

FIG. 1 is a perspective view of the night stand of the present invention;

FIG. 2 is a front view of the night stand of FIG. 1;

FIG. 3 is a side view of the night stand of FIG. 1;

FIG. 4 is a rear view of the night stand of FIG. 1; and,

FIG. 5 is a top view of the night stand of FIG. 1.

The night stand of the present invention is symmetrical about a longitudinal axis and the side views are identical.
